(57) CLAIM

The ornamental design for a “show blanket for horses”, as shown and described.

DESCRIPTION

FIG. 1 is a top perspective view of a “show blanket for horses”, showing a preferred embodiment of my new design;

FIG. 2 is a top plan view of the “show blanket” of FIG. 1; FIG. 3 is a bottom plan view of the “show blanket” of FIG. 1;

FIG. 4 is an end view of the “show blanket” of FIG. 1, taken from either end, as the views from both ends are identical; and,

FIG. 5 is a side elevational view of the “show blanket” of FIG. 1, taken from either side, as the views from both sides are identical.
